UNITED STATES PATENT OFFICE.

GUSTAV EGLOFF AND HARRY P. BENNER, OF CHICAGO, ILLINOIS, ASSIGNEES TO
UNIVERSAL OIL PRODUCTS COMPANY, OF CHICAGO, ILLINOIS, A CORPORATION OF
SOUTH DAKOTA.

METHOD FOR COOLING THE HEATING COILS OF AN OIL-CRACKING APPARATUS.

Original application filed March 23, 1921, Serial No. 454,848. Divided and this application filed January 14, 1925. Serial No. 2,384.

This invention relates to a method for cooling an apparatus for treating hydrocarbon oils and is a division of our co-pending application filed March 23, 1921, Serial No. 454,848 which has eventuated into Patent No. 1,541,553. The invention refers more particularly to that type of construction in which the oil is fed through a heating coil, thence delivered to an expansion chamber where vaporization takes place, the vapors drawn off and subjected to suitable condensing action and the heavier portions thereof returned to the heating coil for further treatment.

In the operation of a cracking apparatus of this type it is necessary to periodically shut the apparatus down for cleaning. In order to do this, it is necessary to cool the entire system, which is accomplished frequently by circulating the raw cold oil through the entire apparatus. This takes time and also results in the oil being sent through a considerable part of the apparatus which is unnecessary. After that, it is sometimes necessary to clean the gases out of parts of the system by steam or otherwise and more particularly out of the expansion chamber where vaporization takes place and the uncondensable gas has been liberated. Time, in the operation of cracking plants, particularly where there are a large number of stills, is a matter of very considerable importance from a commercial standpoint.

The object of the present invention is to provide a method for quickly cooling down the heating coils whereby they may be examined and cleaned of carbon and likewise the expansion chamber.

The apparatus in which this is accomplished is shown in the accompanying drawing in which the single figure is a view, partly in side elevation, and partly in vertical section, of our improved apparatus.

Referring in detail to the drawing, 1 designates the furnace in which is mounted the heating coil 2 which may take the form of a continuous coil of say, 4-inch pipe. The inlet side of the coil is connected by feed pipe 3 to the charging pump 4 connected by the line 4' to the storage tank 18. The discharge side of the coil is connected by the line 6 in which is interposed a throttle valve 5, to the expansion chamber 7. This chamber 7 is provided with a vapor outlet pipe 8, con-

trolled by a throttle valve 8', extending up into a horizontally disposed dephlegmator 9 having the alternately disposed baffles 10. Vapor pipes 11 having throttle valve 12 are provided for conducting the vapors out of the dephlegmator to condenser coil 13. Condenser coil 13 is connected by line 14 having throttle valve 14' to the top of receiver 15. This receiver 15 is provided with suitable pressure gauge and liquid level gauge as shown, and with gas outlet pipe 15' having throttle valve as shown, and distillate draw-off pipe 15'' having a suitable throttle valve as shown. The reflux condensate is returned from the dephlegmator to the heating coil by means of the pipe 16 having throttle valve 17. The discharge or transfer line 6 is provided with a branch 19 having throttle valve 20 leading back to the upper end of the receptacle 18. A throttle valve 21 is interposed in the line 4' and throttle valve 22 is provided in the line 3. Steam may be introduced to the vapor or expansion chamber through the pipe 23 controlled by throttle valve 24 and may be drawn off through the pipe 26 having throttle valve 25.

The apparatus may be operated as follows: Oil may be introduced through the feed line 3 into the heating coil 2 and heated to a temperature of say, 800 degrees F. in the transfer line and delivered in substantially liquid phase to the expansion chamber where vaporization takes place. In this case, the valves 5 and 8' are open. Valves 20 and 24 are closed. The vapors pass out of the pipe 8 into the dephlegmator 9 where the heavier portions are condensed and returned as reflux condensate through the line 16 to the heating coil 2. The uncondensed vapors pass out of the pipe 11 through the condenser and thence to the receiver. A pressure of about 140 pounds may be maintained on the entire system, as for example, in the treatment of a mid-continent fuel oil.

After the system has been run for a more or less extended period of time, carbon is bound to accumulate in the vapor chamber and there is likely to be a tendency for some little carbon to be precipitated in the heating coil. Before cleaning out the heating coil it is necessary to cool down the system and this generally takes a considerable period of time, which time, of course, is lost as far as

use of the apparatus is concerned. However, we have devised a very simple and effective method and means of accomplishing this. To this end we close the valves 5 and 17 5 open the valve 20 and circulate the cool oil through the closed circuit formed by the tank 18, coil 2 and pipes 4' and 19. This forms a relatively short circulation but is nevertheless very effective in cooling the system. At the same time, the valve 8' may be closed and steam injected through the pipe 23 under sufficient pressure to clean out the gases and cool down the expansion chamber.

As another novel feature of the invention, 15 we provide means for preventing the carbon which is precipitated in the expansion chamber from piling up around the draw-off line and thus retarding the discharge of the residuum. This is accomplished by means of a 20 segmental baffle plate 27 which is mounted in the expansion chamber near the draw-off 26 and is segmental in form so as to fit closely around the lower side walls of the drum and may be of the height shown in the draw- 25 ing.

We claim as our invention:

1. A method for cooling the heating coil 30 of a coil and chamber oil cracking apparatus of the character in which oil is continuously supplied to the heating coil, raised to a cracking temperature therein, and thence delivered to the chamber and which includes pipe

connections for cyclically circulating oil from the bulk supply to the heating coil and back to the bulk supply comprising discontinuing the application of heat to the heating coil, ceasing the delivery of oil from the coil to the chamber, continuing the passage of cool oil through the coil, returning the oil subsequent to its passage through the coil to a bulk supply of cool oil, from which supply oil is being delivered to the coil until the coil is sufficiently cooled.

2. A method for cooling the heating coil of a tube and drum oil cracking apparatus of the character in which oil is continuously passed through the heating coil, raised to a cracking temperature therein, and thence delivered to the reaction drum and which includes pipe connections for cyclically circulating oil from the bulk supply to the heating coil and back to the bulk supply, comprising discontinuing the application of heat to the coil while continuing the passage of charging oil through the coil, returning the charging oil which has passed through the coil to a source of cool oil supply without admitting the same to said drum, and in continuing the supply of oil from said source of supply to the coil until the temperature of the coil has been sufficiently reduced.

GUSTAV EGLOFF.
